UNITED STATES PATENT OFFICE.

MICHAEL P. MARONG, OF ROCK GLEN, NEW YORK.

MOTOR-SLEIGH.

1,229,999.

Specification of Letters Patent. Patented June 12, 1917.

Application filed February 16, 1917. Serial No. 149,082.

To all whom it may concern:

Be it known that I, MICHAEL P. MARONG, a citizen of the United States, residing at Rock Glen, in the county of Wyoming and State of New York, have invented new and useful Improvements in Motor-Sleighs, of which the following is a specification.

This invention comprehends the provision of a motor operated sleigh, and embodies a propelling mechanism capable of adjusting itself to road conditions, that is to say that the machine can travel over irregular surfaces and obstructions in the road, without undue jar or vibration to the mechanism, or the occupants of the sleigh.

More specifically stated the invention embodies a plurality of propelling arms adapted to be successively brought into engagement with the ground or surface, in series, whereby the sleigh is propelled without being subject to jerks, bucking or jumping, and with the desired smoothness irrespective of the speed at which the sleigh travels.

One of the chief characteristics of the invention resides in the provision of means for preventing derangement of the propelling mechanism, in event the yieldable means supporting the latter becomes broken, and said means being also utilized in supporting the mechanism the required distance from the ground or surface, which distance must be varied in accordance with the road conditions, and consistent with the depth at which it is desired to have the propelling members penetrate the snow or ice covered surface.

With these and other objects in view which will appear as the invention is better understood from the following detail description, the invention resides in the construction, combination and arrangement of parts as claimed.

In the drawings forming part of this specification like numerals of reference indicate similar parts in the several views and wherein:

Figure 1 is a side elevation of a machine constructed in accordance with my invention.

Fig. 2 is a top plan view of one of the

rear runners showing the operating mechanism.

Fig. 3 is an enlarged view showing a side elevation of one of the rear runners.

Fig. 4 is a vertical sectional view taken on line 4—4 of Fig. 2.

Fig. 5 is a similar view taken on line 5—5 of Fig. 2.

Fig. 6 is a vertical sectional view taken on line 6—6 of Fig. 3.

Fig. 7 is a sectional view taken on line 7—7 of Fig. 3.

Fig. 8 is a detail view partly in section of the swivel connection between the propelling members.

Fig. 9 is a view of the steering knuckle for the front runners.

Referring to the drawings in detail A indicates generally the body of the sleigh which is mounted upon the chassis or frame B, the front runners being indicated at C, the rear runners at D, while interposed between the respective runners and the chassis B are springs E preferably of the elliptical type. The machine is preferably provided with a front axle and steering knuckle of the type commonly employed with motor vehicles, and illustrated in Fig. 9, to facilitate steering of the sleigh, the axle being indicated at 10, and the steering knuckle 11. It is understood that the steering mechanism does not form any part of this invention, and that any suitable steering mechanism may be employed.

As is clearly obvious the propelling mechanism is supported upon the rear runners of the sleigh, and rising from each of said rear runners is a guide 12, the guides being disposed in alinement and are provided for the reception of bearings 13, in which one of the shafts 14 is journaled. There are two shafts 14, the remaining one of which is journaled in bearings 15 mounted upon the runners, the shafts 14 as shown being disposed in parallelism.

Each of the shafts 14 is provided adjacent each end with a series of crank portions 16, while operatively associated with each crank portion of the respective series, is a propelling arm 17, the latter having

a relatively large lower extremity or ground engaging portion 18 from which depends a plurality of spurs 19. It will be noted that the crank portions 16 of each series, 5 are disposed obliquely, and preferably at right angles to each other, so that the propelling arms are successively brought into engagement with the ground or surface, with a view of propelling the sleigh with- 10 out sudden jerks, jumping or bucking of the sleigh. Again, the propelling arms 17 on one shaft are connected with the propelling arms on the other of the said shafts 14, through the instrumentality of 15 a sectional rod or the like, the respective sections 20 of each rod having their adjacent extremities threaded into a sleeve-like member 21 in the manner to provide a swivel connection between each pair of propelling arms of the respective shafts 14. In 20 this manner certain arms of one shaft are brought into engagement with the ground or surface simultaneously with certain of the propelling arms 17 of the other shaft, 25 which provides a propelling mechanism positive and efficient for the purpose intended.

Keyed or otherwise suitably secured to the foremost shaft 14, is a beveled gear 22, 30 which meshes with a similar gear 23 carried by the shaft 24, the latter being connected, preferably by means of a universal joint 25 with the main driving shaft 26. It is of course understood that the latter mentioned 35 shaft is operated by a motor power, and that the foremost crank shaft 14 is simultaneously operated through the gearing connection between these respective shafts. Carried upon the extremities of each of the 40 shafts 14 are toothed gear wheels 27 over which is trained a chain 28 whereby the rearmost shaft 14 is operated simultaneously with the first mentioned shaft 14 and which latter is connected with the main driving 45 shaft 26, as will be readily understood. A plurality of links 29 are pivoted upon the shafts 14, and are also pivotally connected together. Carried by the links at their point of pivotal connection with each other 50 are toothed gear wheels 30 over which the chain 28 is also trained, the gear wheels 30 constituting idlers and serving to hold the chain taut under all conditions.

Pivotedly mounted upon a bracket 31 rising from each of the rear runners at an appropriate point, is a bell crank lever 32. Depending from the extremity of one branch 33 of each lever, and pivotally associated therewith, is a substantially L-shaped 55 arm 34. The short terminal of the arm carries a bifurcated block 35 for the reception of a base 36, which latter supports one or more coil springs 37, the springs being

interposed between the base and the bearings 13, whereby the latter are yieldably supported with a view of permitting the propelling mechanism to yield in accommodating itself to the irregularities in the surface over which the sleigh is being propelled. In other words when the propelling 65 arms are brought into engagement with high places, or humps in the road, one of the shafts 14 together with the propelling mechanism yields to permit the machine to pass over the irregularities with undue jar 70 or vibration to the mechanism, or to the occupants of the sleigh. In addition to these facts, the swivel connection provided by the sectional rods 20 permits the machine to assume an inclined position at one 75 side or the other, without subjecting the propelling arms or any of the component parts of the mechanism to a torsional or twisting strain. Manifestly the connecting rods 20 functionate in a two-fold capacity. 80 The other branch 33' of the bell crank lever is pivotally connected to a link 38, which latter in turn is pivotally connected to a link 29 which rises from the runner as clearly shown in Figs. 3 and 5. Leading from the 85 link 39 is a rod 40 connected with a suitable hand operated mechanism such as a lever 41 for rocking the bell crank lever 32 on its fulcrum, with a view of raising or lowering the propelling mechanism. A pawl 95 and ratchet mechanism is associated with the lever 41 so as to hold the parts in adjusted position. Manifestly the propeller arms can be arranged at different distances from the ground or surface, it being understood that this distance can be varied consistently with the condition of the road, and of course may be varied in accordance with the depth at which it is desired to have the propelling members penetrate the snow or 105 ice covering the surface, in obtaining an effective purchase upon the latter.

Journaled upon each guide for the bearings 13, is a pulley 42 over which is trained a flexible element 43, one end of the latter being connected to the adjacent bearing 13, while the opposite end of the flexible element is connected to the branch 33' of the bell crank lever. It is obvious that the flexible element 43 serves to maintain the bearing and its associated parts in operative position, should for any reason the coil spring 37 become broken or otherwise injured, it being understood that the coil springs provide the main support for the 110 115 bearings.

Mounted upon the foremost shaft 14 is a brake drum 44 preferably embodying a pair of mating sections clearly illustrated in Fig. 7, while surrounding said drum is a 120 125 brake band 45. These parts are of the ordi-

nary well known construction, such as used in automobile construction, and do not form a part of the invention.

It is believed that from the foregoing description the nature and advantages of the invention will be readily apparent, but briefly stated the operation of the machine is as follows: The crank shafts carrying the propelling mechanism are motor operated and are connected in the manner above described with the main driving shaft 26. It is to be understood that the driving shaft is connected with the motor (not shown) by any suitable clutch mechanism, and when the parts are operatively connected the crank shafts 14 are rotated in unison, so that the propeller arms of the respective shafts are successively brought into engagement with the ground or surface in series, adjacent the opposite sides of the machine, whereby the machine or sleigh is propelled over the surface with the desired smoothness. However when it is desired to stop the sleigh, the same is readily accomplished by throwing out the clutch (not shown) which as will be readily understood disengages the main driving shaft 26 from the motor power, and subsequent to this operation, an application of the brake will serve to stop the sleigh. As above stated the brake mechanism is identical with that employed in automobile construction, and a detail description of its construction and operation is not deemed necessary, and has therefore been omitted.

While I have shown and described what I now consider the preferred embodiment of the invention, I desire to have it understood that I do not limit myself to this precise construction and arrangement of parts, and that such changes may be resorted to when desired as fall within the scope of what is claimed.

What is claimed is:

1. The combination with a sleigh having rear runners, of propelling mechanism including spaced parallel shafts journaled between said runners, one of said shafts being yieldably supported, each shaft having a series of crank portions adjacent its opposite ends, propelling arms depending from said cranks, and motor operated means for simultaneously rotating said shafts for the purpose described.

2. The combination with a sleigh having rear runners, of propelling mechanism including spaced parallel shafts journaled between said runners, one of said shafts being yieldably supported, each shaft having a series of crank portions adjacent its opposite ends, propelling arms depending from said crank portions, a swivel connection between the said propelling arms of the re-

spective shafts, and motor operated means for rotating said shafts as and for the purpose described.

3. The combination with a sleigh having rear runners, of propelling mechanism including spaced parallel shafts journaled between said runners, vertically disposed guide members carried by the runners, bearings for one of said shafts being yieldably mounted in said guides, each of said shafts having a series of crank portions adjacent its opposite ends, propelling arms depending from said crank portions, the arms of the respective shafts being connected in pairs, and motor operated means for simultaneously rotating said shafts for the purpose described.

4. The combination with a sleigh having rear runners, of propelling mechanism including spaced parallel shafts journaled between said runners, one of said shafts being yieldably supported, each of said shafts having a series of crank portions adjacent its opposite ends, propelling arms depending from said crank portions, gears mounted upon the extremities of said shafts, motor operated means for rotating one of said shafts, a chain trained over said gears whereby the other of said shafts is rotated simultaneously with the first mentioned shaft, and means for holding said chain taut.

5. The combination with a sleigh having rear runners, of spaced parallel shafts journaled between said runners, one of said shafts being yieldably supported, each of said shafts having a series of crank portions adjacent its opposite ends, propelling arms depending from said cranks, gears fixed upon the extremities of said shafts, a main driving shaft operatively connected with one of the crank shafts for rotating the latter, a chain trained over said gears whereby the other of said crank shafts is rotated simultaneously with and from the first mentioned shaft, a plurality of links pivotally mounted upon said crank shafts, and pivotally connected together, and idle gears carried by said links at their point of pivotal connection with each other for holding said chain taut.

6. The combination with a sleigh having rear runners, of vertically disposed guide members carried by said runners, bearings yieldably mounted in said guides, spaced parallel crank shafts mounted for rotation, one of said shafts being journaled in said bearings, each of said shafts having crank portions, propelling arms depending from said crank portions, and manually operable means for adjusting said bearings and their associated parts to vary the distance of the propeller arms from the ground or surface, and means for holding said parts in adjusted position.

1. The combination with a sleigh having rear runners, of vertically disposed guide members carried by the runners, bearing blocks yieldably mounted in said guides, spaced parallel shafts mounted for rotation, one of said shafts being journaled in said bearings, each of said shafts having crank

portions, propelling arms depending from said crank portions, and means for holding said bearings against casual displacement in event said yieldable supporting means becomes broken.

In testimony whereof I affix my signature.
MICHAEL P. MARONG.
